ABSTRACT

Apparatus for assembling seed capsule halves formed of compressed vermiculite with cavities in each half cooperating to receive a seed before the halves are joined. The apparatus includes a roller and hopper assembly for providing a feed row of capsule halves that are randomly oriented. The feed row passes by a rotating probe that pushes capsules whose cavities face away from the probe into a row that forms capsule covers and allows capsule halves whose cavities face the probe to continue on to form a row of capsule bottoms. A vacuum drum singulator deposits seeds individually into the cavities of the capsule bottoms and the latter approach an assembly station that also receives the capsule covers with their cavities face down. At the assembly station a glue pump deposits drops of liquid on the capsule bottoms whereupon the capsule covers are superposed thereon and cam operated pressers squeeze the two parts together to complete the capsule. The conveyor that brings the capsule bottoms to the assembly station operates at a speed higher than that required to match the rate of cover input and means are provided to reject any excess of capsules before they reach that conveyor. The same conveyor also rejects broken capsule bottoms.

CAPSULE ASSEMBLY MACHINE

This is a division of application Ser. No. 244,484, filed Apr. 17, 1972, now U.S. Pat. No. 3,797,195.

REFERENCE TO RELATED APPLICATIONS

The seed singulator drum employed in the machine of this invention forms the subject matter of the pending application of Hembree, Ser. No. 245,076 filed Apr. 18, 1972, assigned to the FMC Corporation, which application issued on Nov. 6, 1973 as U.S. Pat. No. 3,770,164.

FIELD OF THE INVENTION

This invention relates to apparatus for assembling capsules and more particularly to apparatus for assembling capsules formed of identical halves with cavities in each half formed of frangible material with means for insuring that a single seed is inserted into each capsule assembly.

DESCRIPTION OF THE PRIOR ART

A seed capsule planter that forms completed vermiculite seed capsules into a single feed row using upwardly turning rollers in a hopper is disclosed in the U.S. Pat. to Brink, No. 3,636,897, Jan. 25, 1972, assigned to the FMC Corporation.

Frangible seed capsules of the type which the apparatus of this invention is particularly suitable for performing the assembly are disclosed in the U.S. Pat. to Adams, No. 3,561,159, Feb. 9, 1971, also assigned to the FMC Corporation.

The use of glue drops to join vermiculite capsule halves is found in the U.S. Pat. to Brink, No. 3,555,730, Jan. 19, 1971, assigned to the FMC Corporation.

The use of a rotating vacuum box drum having peripheral needles for picking up small objects such as seeds, with means for directing air under pressure to the needles at one location for dislodging the seeds is known. However, this apparatus has not been found operative for picking up and singulating seeds such as lettuce seeds which have an irregular shape and are exceedingly small and light.

SUMMARY OF THE INVENTION

The capsule assembly machine, of which the present invention is a part, is particularly useful in assembling seed capsules of the type previously mentioned. These capsules are planted at predetermined spacings, so that the young plants need not be thinned. To insure substantially 100% germination, the capsules must be of a material that readily absorbs water and thereupon disintegrates. Moderately compressed vermiculite has been found to meet these requirements. However, capsules formed of this material and meeting these specifications are necessarily rather brittle and frangible; and for these reasons a seed capsule machine that can reliably assemble capsules of this type must have a gentle action.

The number of capsules required to plant even a modest acreage is very large. Since the capsules are to be assembled with the seeds seasonally and in centralized locations, a practical assembly machine must either operate continuously or intermittently with a high rate of delivery of the finished capsules. The present invention, as disclosed here and in the parent application (Pat. No. 3,797,195, issued Mar. 19, 1974) meets these requirements and offers additional advantages.

A principal object of the invention is to provide an automatic adhesive dispensing machine for the capsule halves and for other discs, which will handle fragile discs without breaking or chipping them.

5 A second object of the present invention is to provide an automatic liquid dispensing machine which can operate continuously or in an intermittent mode at a high rate of delivery.

10 A third object of the present invention is to provide an automatic liquid dispensing machine for discs which senses that a vacant space rather than a disc is present and which thereupon interrupts the operation of the dispenser.

15 Other and further objects of the invention should be obvious from an understanding of the illustrative embodiment described hereinafter; and various advantages not explicated herein will occur to one skilled in the art after employment of the described invention in practice.

BRIEF DESCRIPTION OF THE DRAWINGS

FIG. 1 is a diagrammatic perspective illustrating the capsule assembly machine taken from the front and left side thereof.

25 FIG. 2 is a diagrammatic perspective illustrating the progressive steps used to encapsulate a seed in a two-piece capsule.

FIG. 3 is a diagrammatic perspective of the machine of FIG. 1 taken from the front and right side thereof.

30 FIG. 4 is an enlarged side elevation of the capsule hopper, capsule singulator, and capsule orienting mechanism.

35 FIG. 5 is an enlarged vertical transverse section taken along lines 5-5 of FIG. 4 illustrating the capsule orienting mechanism.

FIG. 6 is an enlarged vertical section taken along lines 6-6 of FIG. 5 illustrating the capsule hopper, singulator, and singulating conveyor.

40 FIG. 7 is a vertical transverse section taken along lines 7-7 of FIG. 6 illustrating a portion of the hopper and the singulating rolls.

45 FIG. 8 is an exploded perspective illustrating a portion of the capsule singulating conveyor and conveyor track with associated broken capsule blow-off devices.

FIG. 9 is an enlarged transverse section taken along lines 9-9 of FIG. 4 illustrating broken capsule pieces being blown out of the capsule singulating conveyor.

50 FIG. 10 is an enlarged section taken along lines 10-10 of FIG. 4 illustrating one of the capsule tracks.

FIG. 11 is an enlarged perspective illustrating the capsule orienting mechanism.

55 FIG. 12 is an enlarged fragmentary elevation looking in the direction of arrows 12-12 of FIG. 11 illustrating the capsule covers being deflected off the singulating conveyor, into a capsule track.

FIG. 13 is an enlarged fragmentary operational plan of the portion of the capsule orienting wheel illustrating its relationship to the bottom half of a capsule.

60 FIG. 14 is a plan view similar to FIG. 13 but illustrating a cover half of a capsule being pushed off a singulating conveyor.

FIG. 15 is a vertical section taken along lines 15-15 of FIG. 12 illustrating a capsule cover being pushed out of the singulating conveyor.

65 FIG. 16 is an enlarged vertical section with parts cut away taken substantially along the lines 16-16 of FIG. 3 illustrating the capsule bottom accumulator and a

photo-electric detecting device for determining the upper limits of accumulated capsule bottoms.

FIG. 17 is an enlarged section taken along lines 17-17 of FIG. 16 illustrating the bottom accumulator photo-electric cell which when blocked from its light source stops the singulator conveyor.

FIG. 18 is an enlarged perspective looking in the opposite direction relative to FIG. 17 and illustrating the seed singulating and capsule loading mechanism.

FIG. 19 is a side elevation of the seed singulating and capsule loading mechanism.

FIG. 20 is an enlarged vertical section through one of the seed singulating cones illustrating the desired range of cone angles and also illustrating the preferred cone angle when singulating lettuce seeds.

FIG. 20A is a modified version of the seed singulating ring and seed singulating cone.

FIG. 21 is a plan of the seed singulating and capsule loading mechanism.

FIG. 22 is a front elevation of the seed singulating and capsule loading mechanism, certain parts being broken away to illustrate capsule reject gates.

FIG. 23 is an enlarged vertical section taken along lines 23-23 of FIG. 21.

FIG. 24 is an enlarged vertical section taken along lines 24-24 of FIG. 21 illustrating the mechanism for singulating and loading seeds into a capsule base.

FIGS. 25, 26 and 27 are progressive operational views illustrating the structure for blowing all but a single seed from the seed singulating cones.

FIG. 28 is a horizontal section taken along lines 28-28 of FIG. 22 illustrating the capsule base advancing star wheel and the seed detecting photoelectric sensor.

FIG. 29 is a vertical section taken along lines 29-29 of FIG. 28 illustrating the capsule bottom rejecting gates in a closed position supporting a capsule bottom.

FIG. 30 is a vertical section similar to FIG. 29 but illustrating the gates in an open position discharging a capsule bottom as would occur if a seed was not loaded into the capsule bottom.

FIG. 31 is a diagrammatic horizontal section taken substantially along lines 31-31 of FIG. 23 illustrating certain electrical control components associated with the reject gates.

FIG. 32 is a diagrammatic perspective illustrating the location of the electrical control components relative to the mechanical components of the machine.

FIG. 33 is a front elevation of the capsule combining and gluing mechanism.

FIG. 34 is a side elevation of the mechanism of FIG. 33 looking in the direction of arrows 34-34 of FIG. 33.

FIG. 35 is an enlarged horizontal section taken along lines 35-35 of FIG. 33 illustrating the mechanism for driving the capsule halves through the capsule combining and gluing mechanism.

FIG. 36 is an enlarged vertical section taken along lines 36-36 of FIG. 33 illustrating the gluing mechanism discharging spots of glue onto a capsule bottom.

FIG. 37 is a fragmentary elevation with parts in section taken along lines 37-37 of FIG. 36 illustrating the gluing pump when it is energized and ready to discharge glue spots onto the capsule bottom.

FIG. 38 is a vertical partially arcuate section taken along lines 38-38 of FIG. 35 illustrating the operation of the combining mechanism.

FIG. 39 is a fragmentary plan, with parts broken away, of the capsule bottom underfeed stopping mechanism.

FIG. 40 is a vertical section taken along lines 40-40 of FIGS. 35 and 39.

FIG. 41 is a diagrammatic perspective illustrating the drive mechanism of the seed singulating mechanism, the capsule combining and gluing mechanism, and related conveyors.

FIG. 42 is a detail in elevation of part of the drive mechanism of FIG. 41.

FIG. 43 is a section taken along lines 43-43 of FIG. 42.

FIG. 44 is a section taken along lines 44-44 of FIG. 43.

DESCRIPTION OF THE PREFERRED EMBODIMENT

In the preferred embodiment of the invention, the capsules are assembled from identical halves in the form of discs, each of which has a shallow cavity, and when the discs are assembled with the cavities facing one another a composite seed containing cavity is provided. All of the capsule halves are preferably introduced from a single hopper and are singulated into divergent processing rows, one being a row of capsule bottoms for receiving the seeds and the other a row of capsule covers to be assembled with the seed containing bottoms, thereby forming the composite seed forming capsule. The apparatus of the present invention sorts the capsule halves into the aforesaid two rows reliably, rapidly and without damage to the discs.

In order that both processing rows of capsule bottoms and capsule covers originating from the same hopper have equal flow rate, reliance cannot be made completely on statistical probability of these rows being equal and therefore it is contemplated under the present invention that the row of capsule bottoms be advanced more rapidly, about 30% faster, than that of the capsule covers with any excess capsule bottoms disposed of automatically. It is also important that if the crop is to be planted to a stand, care be taken that all capsule bottoms are provided with a seed before they are mated with the capsule covers, and that capsule bottoms that may possibly have been damaged or broken during their more lengthy processing in the apparatus, be disposed of automatically and without interference with their basically continuous flow through the capsule making apparatus.

The manner in which the above and other criteria are met by a machine which assembles compressed vermiculite capsule halves encompassing lettuce seeds (which incidentally is believed to represent one of the most stringent set of requirements) at a rate of about 200 completed capsules per minute will now be briefly outlined.

Identical vermiculite capsule halves formed of vermiculite compressed at a ratio of about 4-1 to 6-1 and with cavities in one face only are provided. These are of flat discs about $\frac{1}{4}$ inch in diameter and about $\frac{1}{8}$ inch thick. The preformed capsule halves, which will eventually be joined together cavity face to cavity face, are first placed in a hopper which has upwardly turning rubber covered rollers and a chute construction that delivers the capsules in vertical edge to edge relation to a moving conveyor having saddle pockets. This moving row of capsules is the feed row.

With central hopper feed, the feed row of capsules must be divided into two processing rows, a row of capsule bases or bottoms and a row of capsule covers. These rows must be formed continuously without damage to the capsules. Under the present invention the feed row capsules are sorted into the aforesaid two processing rows on the basis of their cavity orientation. All capsules whose cavities face in one direction are pushed out of the feed row and form one processing row, whereas those halves whose cavities face in the other direction are allowed to continue on, to form the second processing row. More specifically, a rotating wheel having circumferentially spaced projections or probes is synchronized with the moving row of capsules. The wheel is so disposed that the probes push those capsule halves having blank faces facing the probes out of the feed row and into a processing row that constitutes the capsule covers. The same probes, however, enter the cavities of those capsule halves that face the probes, and the probes are short enough so that they do not dislodge these capsule halves, and hence allow them to continue on in the feed row. The latter group of capsules, in the preferred embodiment of the invention, are brought into a horizontal plane with their cavities facing up and thereby form a row of capsule bases or bottoms.

It is essential that every capsule have a seed and that no capsule have more than one seed. A further requirement is that the flow of capsules be continuous and rapid. In accordance with the present invention the seeds are singulated with a combined vacuum-air pressure eject drum having conical seed pickup pockets and doubles ejecting air jets, forming the subject matter of the aforesaid copending application of Hembree.

The row of capsule bottoms enters a continuously moving star wheel having funnels above the star wheel pockets. The aforesaid singulating drum picks up and drops single seeds into each funnel and hence to each cavity pocket. The seed drop is monitored by a photoelectric inspection system which controls rapidly operated gates at the base of the star wheel which supports the bottoms. This system rejects all capsules that have not received seeds.

The capsule bottoms having seeds proceed into a conveyor that brings them to a capsule assembling station. Since there is no way to insure equal distribution of capsule covers and capsule bottoms in the two processing rows, under the present invention provision is made to supply an excess of capsule bottoms with seeds, and to remove excess capsule bottoms from the row before they reach the assembly station. More specifically, in accordance with the present invention, the length of the processing row that feeds the capsules to the assembly station is monitored and under normal operation this row will, from time to time, exceed a predetermined length. When this occurs, a photoelectric sensor system rejects capsules before entering the row, using the same reject gate mechanism that rejects those capsule bottoms which have not received seeds from the singulating system.

Since the capsule bottoms must pass through a chute that leads to the seed introduction star wheel and through that wheel, there is a possibility that a few of the bottoms may be damaged during this process. In accordance with the present invention, the conveyor which supplies the processing row of capsule bottoms to the assembly station automatically rejects capsule

bottoms which are not completely whole. This operation is performed by making the aforesaid conveyor in the form of parallel belts running at different speeds, whereupon the capsules are rotated as they are advanced toward the assembly station. These belts are so spaced that if a piece is broken off one of the capsule bottoms the defective disc will fall between the belts and hence will not be further processed.

No monitoring of the processing row of capsule covers is required. As previously mentioned, this row is assembled from capsules which have been pushed away by the sorting probe and they fall into a generally vertical chute which turns the capsules into a horizontal plane with their cavities down. If an excess of capsule covers is delivered the chute will be filled right up to the sorting point and an excess of capsule covers will be pushed over the end of the chute and recaptured.

Before the capsule components, namely, capsule bottoms with seeds and the covers are brought together at the assembly station an adhesive is applied to the capsule bottoms. This operation is performed by dropping several small drops of glue onto the moving capsules as they pass beneath the synchronized glue pump. The glue pump is timed by a mechanism moving in synchronism with a star wheel that spreads the capsules out somewhat and advances them one by one beneath the pump. Under the present invention, the glue pump has an apertured bottom reservoir cylinder with plungers which are quickly forced down through the apertures to eject drops of glue onto the bottoms. As the assembly station, the capsule covers must be synchronously brought into alignment with the capsule bottoms having seeds therein and glue deposits thereon, gently and without smearing the glue. This is accomplished by advancing the capsule bottoms into a lower star wheel and the capsule covers into an upper star wheel aligned and rotating with the lower wheel. The capsule covers are propelled at a sufficient speed over the bottom so that they become aligned with and drop directly upon the glue drops on the capsule bottoms and accordingly will not be smeared during juxtaposition of the two capsule halves. After the capsule covers have been superposed with and are resting on the capsule bottoms, a cam operated plunger gently squeezes the capsule covers against their bottoms and completes the bond. The completely assembled capsules are thereafter continuously discharged from the assembly station star wheel units onto a take-away conveyor.

All of the aforesaid actions take place rapidly and with gentle handling of the capsules, without concern about the numerical distribution resulting from the sorting operation after the capsules enter and leave the feed row. None of the assembled capsules will be without seeds and none will have more than one seed. Despite the fragility and rigidity of the capsule material, and despite the difficult handling problems presented by certain seeds such as lettuce seeds, the capsule machine of the present invention can be utilized to produce a large number of assembled seed capsules in a relatively short time.

It will be understood that although the preferred embodiment of the invention has been described in connection with the planting of vermiculite capsules bearing lettuce seeds, this embodiment merely represents one of the most severe requirements in terms of fragility of the capsules, intractability of the seeds and high speed requirements. Thus, it will be apparent that the

capsule assembly machine of the present invention will be suitable for the assembly of capsules of the type described under less stringent conditions, namely, capsules which are not as fragile as those made of vermiculite, and seeds or other similar articles which are not as difficult to singulate as lettuce seeds.

In general, the capsule assembly machine 40 (FIGS. 1-3) of the present invention includes a capsule hopper 42 which receives a bulk supply of identical capsule halves in the form of discs. Pairs of capsule halves are subsequently sealed together to define a capsule C (FIG. 2) having a capsule base or bottom C_b and a capsule cover C_c. Each capsule bottom and cover includes a central cavity 44 which faces each other when the capsule halves are properly oriented so as to accommodate and seal a single seed S therein. The bulk supply of capsule halves in the hopper 42 are singulated by a roller type capsule singulating mechanism 46 which includes a singulating conveyor 50 that advances the row of singulated capsule halves to a capsule orienting mechanism 52. The orienting mechanism 52 senses the position of the capsule cavity 44 and deflects all capsule halves having cavities facing the rear of the machine out of the conveyor 50, into a first processing row partially defined by a capsule cover accumulating chute or track 54. The remaining capsule halves having cavities facing forward are the capsule bases C_b and are discharged down a second processing row partially defined by a capsule bottom accumulating chute or track 56. Each capsule bottom C_b is moved below a seed singulating and capsule loading mechanism 58 at a seed dropping station which drops a single seed S (FIG. 2) into the cavity 44 in each capsule bottom. Each loaded capsule bottom is then moved under a gluing mechanism or pump 60 of a capsule combining and gluing mechanism 61 which applies a plurality of glue spots 62 onto each capsule bottom. The capsule bottoms C_b and capsule covers C_c are then moved into a capsule combining mechanism 64 and are pressed together to form complete sealed capsules C.

Capsule Hopper, Singulating Mechanism and Orienting Mechanism

More particularly, the capsule hopper 42 and capsule singulating mechanism 46 (FIGS. 4-8) serves to receive capsule halves in bulk and singulate them so that they all lie singularly and on edge in a feed row in a common vertical plane.

The capsule hopper 42 comprises a housing 70 (FIGS. 4-6) having a narrow neck 72 which allows the capsule discs to gravitate downwardly into one end of a capsule agitating housing 74 having an open lower end defined by inwardly and downwardly inclined walls 76. The walls 76 deposit the capsule halves upon a pair of counter rotating capsule singulating rolls 78 and 79 which are mounted on shafts 80 and 81 journaled in the housing 74. The capsule contacting surfaces of the rolls 78 and 79 are driven upwardly as clearly shown in FIG. 7, and have screw threads 82 (FIG. 4) formed thereon which serve to prevent capsule halves from wedging crosswise between the counter rotating rolls since the screw threads on one roll are arranged to cause the contacted capsule edge to move to the right while the threads on the other roll will tend to move the capsule to the left.

In order to prevent packing of the capsule halves above the singulating rolls 78 and 79, a capsule agit-

ating brush 84 (FIG. 6) is keyed to a shaft 86 journaled in side walls of the capsule agitating housing 74. The brush includes a plurality of elongated resilient brush bristles 88, and when the brush is rotated the bristles project downwardly between the rollers to gently agitate the capsule halves.

When the capsule halves or discs become aligned in a vertical plane parallel to and passing between the rolls 78 and 79, the capsule halves gravitate downwardly between vertical guide plates 90 and 92. The plates 90 and 92 are spaced apart a distance only slightly greater than the thickness of the capsule halves for providing a supply of capsule halves which gravitate into a feed row defined by the capsule singulating conveyor 50.

The singulating conveyor 50 is an endless conveyor that is trained around sprockets 96 and 98 secured to shafts 100 and 102, respectively. The shaft 100 is the input shaft of a right angle gear box 104 which gear box is rigidly secured to the frame F of the capsule assembly machine 40. The shaft 102 is connected to an output shaft of a gear box 108 that is secured to the frame F and is driven by a gear motor 110 through a chain drive 112. The endless conveyor 50 includes a plurality of interconnected links 114 (FIG. 6) each having a saddle pocket 116 for receiving a capsule C. As shown in FIGS. 5-6, the pocket forming portion of the links 114 move between the capsule guide plates 90 and 92 in the direction indicated by the arrow in FIG. 6, and gravitationally receive the vertically aligned capsule halves.

The capsule halves or discs are somewhat fragile and may break or form debris and dust particles if handled roughly. Since broken capsule halves, dust, debris or the like is apt to foul parts of the capsule assembly machine, provision is made for discharging this material from the machine. In this regard and as best illustrated in FIGS. 8 and 9, the guide track assembly 117 for the singulating conveyor 50 includes broken capsule blow-out devices 118 and 120. The guide track assembly includes fabricated side guide members 122 and 124, a capsule supporting and guiding track 126 disposed therebetween, an upper conveyor guide track 128 (FIG. 4) for supporting the upper run of the conveyor, and lower conveyor tracks for supporting the lower run of the conveyor defined by the upper surfaces of the side guide members 122 and 124 as indicated in FIG. 5.

The blow-off device 118 (FIG. 8) is disposed adjacent the upper run of the singulating conveyor 50 and includes a manifold 130 secured to the guide member 124 and connected to a source of blow-off air under super-atmospheric pressure by a conduit 132. A series of upper holes 134, intermediate holes 136, and lower holes 138 in the guide member allows the high pressure air to blow dust and broken capsule parts off the conveyor through an upper slot 140, an intermediate slot 142, and a lower notch 144, respectively, formed in the outer guide member 122.

The blow-off device 120 (FIGS. 8 and 9) is located adjacent the sprocket 96 (FIG. 4) at a point where the capsules are rolling on the capsule supported turret 126. The blow-out device 120 comprises a manifold 146 that is connected to a source of superatmospheric pressure air by a conduit 148, and is secured to the guide member 124 for directing air through a series of holes 150 therein. An arcuate discharge slot 152 in the member 122 has its lower edge aligned with the capsule

track. Thus, cracked or broken capsules will roll until the lower portion is blown out of the slot 152, thereby allowing the upper portion of the broken capsule half to drop into the path of the air blast and then be blown through the slot as clearly indicated in FIG. 9.

As best shown in FIGS. 4 and 5, the capsule singulating rolls 78 and 79 are driven from an output shaft of the gearbox 108 which is coupled to a drive shaft 154. The shaft 154 (FIG. 5) is connected to and drives the singulating roll shafts 80 and 81 by a chain drive 156 which includes idler sprockets 158 and 160 and drives the shafts 80 and 81 in the direction indicated by the arrows in FIG. 5. The capsule agitating brush 84 (FIG. 6) is driven by a chain drive 164 (FIG. 4) which is connected to the output shaft 102 of the gear box 108 and includes an idler sprocket 166.

Since the capsule halves which enter the pockets 116 of the singulating conveyor 50 do not have their seed receiving cavities 44 facing in a common direction as indicated in FIG. 6, it is necessary to separate the capsule halves into two groups with the halves in each group having the cavities facing in a common direction. As viewed in FIG. 4, those capsule halves which have their cavities 44 facing the rear are used as capsule covers Cc and are deflected off the singulating conveyor 50 for collection and accumulation in the capsule cover track or chute 54. The remaining capsule halves all have their cavities 44 facing forwardly and are used as capsule bases or bottoms Cb. The capsule bottoms Cb are conveyed in a second processing row to the bottom capsule track or chute 56 for collection and accumulation.

The capsule orienting mechanism 52 (FIGS. 4, 5 and 11 to 15) is provided for orienting the capsule halves into covers and bases as above indicated. The capsule orienting mechanism 52 comprises an orienting wheel 170 which is keyed to an output shaft 172 of the right angle gear box 104. The orienting wheel 170 includes a plurality of equally spaced capsule push-off probes or pins 174 projecting radially outward from its periphery to enter the pockets 116 of the singulating conveyor 50 at a push off point P in axial alignment with the center of the associated capsule cavities 44. If the cavity 44 in a capsule half is facing the wheel 170 at the push-off point P, which point is the point of tangency of the wheel with the conveyor 50, as indicated in FIGS. 11, 12 and 13, a push-off pin will enter the cavity 44 of that capsule half and, accordingly, will allow that capsule half to move past the orienting mechanism 52 to the bottom accumulating track 56. However, if the capsule half at the push-off point P has its flat surface facing the wheel 170, the associated pin 174 will gauge this flat surface and will push the capsule half off its supporting track 126 as indicated in FIGS. 14 and 15 thereby discharging the capsule half into the capsule cover accumulating track 54.

As illustrated in FIGS. 12 and 15, the capsule covers Cc which are pushed off the track 126 at the pushoff point P are confined between guiding surfaces 176 and 178 and are guided into the cover track 54 by a curved surface 180 of a guide plate 182. The slope of the curved surface 180 is quite steep so that when the accumulating track 154 is completely filled the capsule covers Cc which are thereafter pushed off the track 126 by the orienting mechanism 52 will be forced outwardly of the cover accumulator track 54 over the upper end 184 (FIG. 12) of its outer left rail 186 into a chute 188 as

illustrated by the dotted line arrows in FIG. 12. The overflowing covers then slide or roll down the chute 188 and are discharged from the lower end 190 (FIG. 3) thereof into any suitable type of collecting device such as a container.

The capsule bottoms Cb which are moved past the orienting mechanism 52 by the singulating conveyor 50 are discharged directly into the open upper end of the capsule bottom accumulating track 56. As illustrated in FIG. 10, the track 56 is formed from a plurality of bars 192 which are rigidly secured to spaced brackets 193 to hold the several bars 192 in spaced relation relative to each other thereby allowing fragments of capsule halves to gravitate out of the track 56 between the bars. 15 As illustrated in FIGS. 16 and 17, the bottom accumulator track 56 receives the capsule bottoms Cb when standing on end and twists the capsules into a horizontal position with the cavities 44 directed upwardly before reaching the discharge end thereof. A light source 194 and opposed photoelectric cell 196 are mounted to the frame F by bracket 198 to direct a light beam through the track 56 at the photoelectric cell 196. The capsule bottoms Cb normally accumulate in the lower portion of the bottom accumulating track 56 in abutting relation. However, if the capsule covers accumulate to a point above the photoelectric cell 196 thereby blocking the light to the cell 196, the photoelectric cell opens the circuit to the motor 110 (FIG. 4) thereby stopping all of the components of the singulating mechanism 46 and orienting mechanism 52 until the supply of bottoms Cb is reduced and the photoelectric cell 196 again sees light.

Seed Singulating and Capsule Loading Mechanism

35 The seed singulating and capsule loading mechanism 58 (FIGS. 18-31) is provided for singulating a single seed S (FIG. 24) from a bulk supply of seeds, and to load the single seed S into the cavities 44 in each capsule base or bottom Cb as it moves therewith. The mechanism 58 also includes means for rejecting capsule bases from the system in the event a seed S is not loaded into the capsule base and also in the event the accumulated supply of capsule bottoms loaded with seeds exceeds a predetermined maximum amount.

40 The mechanism 58 (FIGS. 18-22) generally comprises a capsule bottom conveying system 210, a capsule bottom reject device 212, a seed singulator 214, and a capsule loading mechanism 216. The capsule base reject device 212 is controlled either by a seed detecting or inspecting photoelectric device 218 or a bottom oversupply accumulator photoelectric device 220.

45 More particularly, the capsule bottom conveying system 210 (FIGS. 18, 19, 21 and 28) receives the capsule bottoms Cb from the accumulating track 56 and directs the abutting capsule bottoms onto the upper run of a feed conveyor belt 224. The conveyor belt 224 is trained around a drive pulley 226 keyed to a drive shaft 228 (FIGS. 18 and 21) journaled on a bracket 230 secured to the frame F and an idler pulley 232 journaled on a bracket 233 mounted on the frame. While on the conveyor 224 the capsule bottom Cb are guided by edge rails 234 (FIG. 28) and top rails 236. The feed conveyor 224 advances the abutting capsule bottoms Cb over a deadplate 237 into pockets 238 of a star wheel 240 which is keyed to a shaft 242 journaled in the frame F and driven in the direction indicated by the arrows in FIG. 28. The star wheel 240 slidably ad-

vances the capsule bottoms over the deadplate 237 and between the pockets 238 and an arcuate edge guiding surface 244 of a guide plate 246. The deadplate 237 includes a discharge opening 248 (FIGS. 28-30) in the path of movement of the capsule bottoms, which discharge opening 248 is normally closed by a pair of reject gates 250 and 252 of the reject device 212 which normally allows the capsule bottoms to move therewith. The reject gates 250 and 252 are connected to the shafts of rotary solenoids 254 and 256 by arms 258 and 260, respectively, as best illustrated in FIGS. 23 and 28-30.

The capsule bottoms *Cb* which move past the gates 250 and 252 in their normal path of travel slide off the deadplate 237 between pairs of spaced edge guiding rails 262 (FIGS. 21 and 28) and cover guide rails 264 secured thereto and to the frame *F*. As the capsule bottoms advance along the deadplate 237, they become supported upon two spaced endless belts 266 and 268 of a base accumulator conveyor 270 which belts are trained around pulleys 272 and 274 (FIG. 28) journaled on the frame. The belts 266 and 268 are driven in the direction of the arrows, but are driven at different speeds so that the capsule bottoms *Cb* will rotate as indicated in FIG. 21 causing broken capsule halves to separate and fall between the belts 266 and 268 for discharge from the system.

The seed singulator 214 (FIGS. 18-27) comprises a driven vacuum singulating drum or wheel 280 (FIGS. 23 and 24) having a vacuum chamber 282 partially defined by an annular ring 284 of the wheel. A plurality of single seed orificed plugs or suction nozzles 286 are disposed at equal intervals around the ring 284. The singulating wheel ring 284 defines one wall of a bulk seed hopper 288 and is driven relative thereto for first drawing seeds into the conical suction nozzles 286 and thereafter moving the nozzles 286 past air blow-off pipes 290 and 292 which blow all but one seed out of each suction nozzle. Continued rotation of the wheel moves the nozzles into registration with a single seed blow-off device 293 wherein the single seed *S* in each nozzle is blown by air under pressure into the loading mechanism 216.

More particularly, the seed singulator 214 is mounted on the housing 296 (FIGS. 22, 23 and 41) of a right angle gear box 298 which is secured to the frame *F*. The gear box 298 includes an input shaft 300 coupled to a drive shaft 302 by a sleeve 304. The drive shaft is connected in driving engagement to the shaft 242 of the star wheel 240 by a chain drive 306, and is connected to a variable speed motor 308 by a chain drive 310 thus driving the seed singulator 214 and the capsule advancing star wheel 240 in timed relationship. The gear box 298 includes an output shaft 312 (FIG. 23) which projects outwardly from a flanged end portion 314 thereof. A stationary air and vacuum manifold 316 is rigidly secured to the flanged portion 314 of the gearbox 298 and includes a tubular neck 318 which projects outwardly thereof for rotatably supporting the singulating wheel or drum 280.

The singulating wheel 280 (FIG. 23) comprises the ring 284 which is rigidly secured in flanged end walls 320 and 322 as by bolting. The inner edge of the walls 320 and 322 are rotatably received on the sleeve 318 and are sealed in airtight engagement thereto by O-rings 324 fitted in grooves in the inner edges of the walls. A flanged bushing 326 is rigidly connected to the

outer wall 322 of the wheel as by bolting and includes a tubular sleeve 328 which is journaled within the neck 318 and is keyed to the output shaft 312 of the gearbox 298.

As best shown in FIGS. 18 and 23, the manifold 316 is connected to a source of vacuum preferably at about 8-10 inches of mercury by a conduit 330 which communicates with the vacuum chamber 282 in the singulating wheel 280 through conduit 332 and port 336. However, a vacuum within the range of 6-25 inches of mercury has been used successfully. Similarly, an air supply conduit 338 is connected between the manifold 316 and a source of air preferably at about one-half to one psig. However, when operating under increased vacuum a blow-off pressure within the range of about 1-4 psig has been used. The air flows from the conduit 338 through passage 340 in the manifold to the single seed blow-off device 293.

The single seed blow-off device 293 is disposed within the vacuum chamber 282, and includes a sleeve 346 (FIGS. 23 and 24) which communicate with the passage 340 and rigidly secured in a bored portion of the manifold neck 318. A piston 348 is slidably received in the sleeve 346 and is sealed thereto by an O-ring 350. The piston is urged downwardly by a spring 352 and has its lower end secured in an arcuate sealing shoe 354 preferably of plastic such as Teflon or Nylatron. A passage 356 through the piston 348 and sealing shoe 354 communicates with the blow-off air in the sleeve 346 and registers with each seed suction nozzle 286, in turn, as the nozzles move therewith to blow the single seed *S* out of each nozzle as illustrated in FIG. 24. The shoe 354 bears against the inner surface of the ring 284 with sufficient force to provide a seal between the low pressure air in the vacuum chamber 282 and the air at superatmospheric pressure within the blow-off device 293.

As illustrated in FIG. 23, each of the suction nozzles 286 is held in a counterbored port 358 in the ring 284 by a setscrew 360, and is sealed to the port by an O-ring 362. Each nozzle 286 (FIG. 20) includes a first annular groove 366 to receive the O-ring 362, and a second annular groove 368 to receive the associated set screw 360. A relatively large diameter bore 370 leads to an orifice 372 which when handling lettuce seeds is preferably about 0.016 inches in diameter. However, when handling other seeds such as cabbage, broccoli or cauliflower seeds which are round, the orifice diameter range may be within about 0.0135 - 0.040 of an inch.

The orifice 372 leads into a frusto-conical seed receiving cavity 374 having its walls preferably converging at an angle of about 90° when handling the lettuce seeds. When handling other types of seeds such as cabbage, broccoli, or cauliflower seeds which are round as mentioned above, it has been determined that the angle of convergence may vary between about 120° and 45°. It is apparent that if larger seeds or other articles are to be singulated, the diameter of the orifice 372 and the configuration of the seed receiving cavity 374 may be varied to accommodate the particular size seed or the article being singulated.

A modified form of the singulating wheel ring 284a is illustrated in FIG. 20A wherein the ring is thinner in cross-section and the orifice 372a and seed receiving frusto-conical cavities 374a are drilled directly into the ring 284a. Such a singulating ring is ideally suited for

use when encapsulating only one type of seed or other article.

As previously mentioned, the seed singulating drum or wheel 280 defines one wall of the bulk seed hopper 288. The hopper 288 (FIGS. 21, 22 and 24) additionally comprises a main chamber 390 (FIG. 24) and a final blow-off chamber 392 separated by a vertical partition 394. The hopper 288 is defined by sidewalls 396, a front wall 398, a rear wall 400, a floor 402, a roof 404 covering the final blow-off chamber 392, and a hinged screen door 406 covering the main chamber. The door 406 will allow air blown into the hopper to vent from the hopper 288 and may be opened to dump a bulk supply of seeds into the hopper. Because air is continuously being blown into the hopper, the hopper is maintained at a slight superatmospheric pressure even though it is vented through the screen door 406. Arcuate felt strips 407 and felt end strips 408 and 410 are secured to the hopper sidewalls 396, floor 402 and rear wall 404 and bear against the rotating singulating wheel 280 to prevent seeds from escaping from the hopper. The hopper 288 is held in place by a spring loaded latch 411 (FIGS. 21, 22 and 24) that is connected between the manifold 316 and the hopper 288.

In order to prevent packing of the bulk supply of certain types of seeds, it is desirable to blow air into or through the seeds to prevent the seeds from clinging to each other. Such air treatment will hereinafter be referred to as "fluidizing" and is accomplished by directing air at about 1 1/2 to 3 psig. into the lower end of the hopper 288 from a supply conduit 414. It will be understood, however, that certain seeds such as lettuce seeds do not readily fluidize and accordingly when handling these seeds air is not directed into the lower end of the hopper. However, as described below, blow-off air is being continuously directed into upper portions of the hopper and this air also serves to fluff or fluidize the seeds.

As the singulating wheel 280 moves upwardly through the hopper and moves out of the bulk supply of seeds within the hopper, the vacuum within the vacuum chamber 282 draws a plurality of seeds S into the seed receiving cavity 374 of each vacuum nozzle 286 as indicated in FIG. 25. Continued upward movement of each nozzle 286 moves the nozzle past the first air blast pipe 290 (FIG. 26) where air preferably at about 14-16 inches of water gauge pressure blows most of the excess seeds S out of the seed receiving cavity 374 as illustrated in FIG. 26. Each nozzle 286 then moves past the second air blast pipe 292 wherein another blast of air preferably within the range of about 14 to 16 inches of water blows all but a single seed S from the nozzle cavity 374, which single seed completely blocks the air flow into the orifice 372 as indicated in FIG. 27. However, air within the range of between 10-30 inches of water has been used successfully and this pressure is dependent upon the vacuum used in the singulating drum. The single seed S and nozzle 286 rotate with the wheel 284 until the passage through the nozzle 286 registers with the passage 356 in the blow-off device 293. At this time, the superatmospheric pressure within the nozzle 286 blows the single seed S from the singulating wheel 214 to the capsule loading mechanism 216.

The capsule loading mechanism 216 (FIGS. 21, 23 and 24) comprises a disc 420 that is disposed above and is connected to the capsule base star wheel 240 and to a hub 422 keyed to shaft 242. The disc 420 is pro-

vided with a plurality of apertures 423 disposed immediately above and concentric with each pocket 238 in the star wheel 240. A plurality of seed guiding open ended funnels or cones 424 are rigidly secured on the disc 420, with one cone being aligned with each of the disc apertures 423, and also with the cavity 44 (FIG. 24) in the capsule bottom Cb aligned therebelow. Thus, each suction nozzle 286 drops its single seed S into the wide upper end of the associated funnel or cone 424, which cone guides the single seed down into the cavity 44 in the associated capsule bottom Cb.

It is, of course, essential that each capsule base Cb receive a seed S. Accordingly, the seed detecting photoelectric device 218 is provided to detect each seed as it is dropped into the capsule bottom Cb. If a seed is not dropped into the capsule bottom, the photoelectric device 218 energizes the capsule bottom reject device 212 to discharge that capsule bottom from the machine as shown in FIG. 30.

The seed detecting or inspecting photoelectric device 218 (FIGS. 28, 31 and 32) comprises a light source 430 which directs a beam of light against the seed S as it is dropped from the nozzle 286 to the loading funnel 424 into the capsule bottom Cb. If a seed S is dropped, light reflects off the seeds and into a photoelectric cell 432. If the cell 432 sees reflected light, the reject gates 250 and 252 remain closed. If the cell 432 does not see light reflected off the seed, the photoelectric cell 432 sends a signal to the solenoids 254 and 256 of the reject mechanism 212 thereby opening the gates and discharging the empty capsule base Cb.

Provision is also made for opening the reject gates 250 and 252 in the event an excessive number of filled capsule bottoms Cb accumulate downstream of the seed singulating and capsule loading mechanism 58. In this regard, the bottom accumulator overfeed photoelectric device 220 (FIGS. 31 and 32) is provided and includes a light source 434 and a photoelectric cell 436. The photoelectric cell 436 includes a time delay circuit which allows spaced capsule bottoms to move therewithout sending a signal to the reject mechanism 212. However, if a line of abutting capsule bottoms Cb accumulate between the light source 434 and cell 436 so that the cell no longer sees light, the cell 436 activates the reject mechanism 212 to open the gates 250 and 252 until such time as the cell 436 again sees light.

The opening and closing of the reject gates 250 and 252 (FIG. 31) is under the control of normally closed reed or vane switches SW-1, SW-2 and SW-3 which are opened when each of a plurality of fingers 440 pass through the switches. As shown in FIGS. 23, 31 and 32, the fingers 440 are formed on the end of a disc 442 that is secured to an extension of the shaft 242 for rotation therewith. As indicated in FIG. 31, the switch fingers 440 are spaced equal distances apart and are equal in number to the pocket defining teeth of the advancing star wheel 240. Switch SW-1 is a scanning reset switch which terminates the seed scanning cycle shortly before the seed receiving cone of the capsule loader moves out from below the seed blow-off point. Thus, as shown in FIG. 31, the photoelectric cell 432 may detect a seed from the beginning of a cycle until switch SW-1 is open by one of the fingers. The switch SW-1 is opened after the capsule to be loaded with a seed has moved a distance equal to approximately 1/4 of the width of a pocket 238 from the seed blow-off point.

The switch SW-2 is a reject gate opening switch which will determine when the reject gates will open if a seed has not been detected, and the switch SW-3 is a reject gate closing switch which will close the gate when actuated in the event the gates have been opened. It will be noted that the reject gate opening switch SW-2 is positioned to be opened by one of the fingers 440 after the star wheel 240 has rotated a distance of about one-half a pocket 238 from the illustrated position, and that the closing switch SW-3 will engage a finger when the star wheel 240 has rotated about an additional one-quarter of a pocket width from the illustrated position. It will be noted further that twelve pockets 238 (FIG. 31) are provided in the capsule advancing star wheel 240 and that each switch will be activated twelve times per revolution of the star wheel.

The electrical control circuit for controlling the above operation is within the skill of the art and accordingly will not be described in detail.

Capsule Combining and Gluing Mechanism

The capsule combining and gluing mechanism 61 (FIGS. 33-40) comprises in general the gluing mechanism or pump 60 which receives capsule bottoms Cb each having a seed S therein from the base accumulating conveyor 270 (FIGS. 28 and 35). The glue pump 60 preferably applies four spots of glue 62 to each continuously moving capsule bottom Cb and then advances each glued capsule bottom into the combining mechanism 64. Each glued capsule bottom Cb then moves below capsule covers Cc which are received from the lower end of the capsule cover accumulating track 54 (FIG. 34) and drops onto the glue spots 62. The combining mechanism 64 then applies a compressive force to the capsule halves to seal them together for subsequent discharge onto a take-away conveyor 500 driven by a motor 501 (FIG. 41).

More particularly, the capsule combining and gluing mechanism 61 comprises a capsule conveying mechanism 502 as best illustrated in FIG. 35. The conveying mechanism 502 includes a feeder star wheel 504 which receives capsule bottom Cb from a feed conveyor 505 (FIGS. 35 and 41) defined by spaced belts 505a and 505b trained around a drive pulley 506 and a driven pulley 507. The base accumulating conveyor 270 includes the previously mentioned belts 266 and 268 that are trained around the drive pulley 506 and another drive pulley 508 (FIG. 43), which pulleys are driven at different speeds as will be described.

The capsule bottoms Cb are received in pockets 510 of the star wheel 504 which is keyed to a shaft 512 and is driven in the direction indicated by the arrows in FIG. 35. The capsule bottoms Cb are slidably advanced over a deadplate 513 having arcuate slots 514 therein to allow glue to pass therethrough in the event glue is dispensed when a star wheel pocket 510 is empty. A guide plate 515 secured to the deadplate 513 has an arcuate guiding surface 516 which guides the capsule bottoms Cb onto a support disc 517 and into pockets 518 formed in the periphery of a lower star wheel 520 of the combining mechanism 64. The combining mechanism 64 also includes an upper or capsule cover star wheel 522 which is spaced above the lower star wheel and has pockets 524 therein which are aligned with the lower pockets 518 and receive and advance the capsule covers Cc. The capsule supporting disc 517 and the star wheels 520 and 522 are keyed to a shaft 526 that is

driven in the direction of arrow in FIG. 35. The star wheels 520 and 522 are spaced apart vertically to permit the pocket defining fingers 528 of the glue mechanism star wheel 504 to move therebetween as indicated in FIG. 35. Also, the space between star wheels permits a stripper finger 530 to be inserted therebetween to strip the completed and sealed capsules therefrom for discharge over a deadplate 532 onto the take-away conveyor 500. During their travel around the combining mechanism 64, the capsule bottoms Cb are guided by an arcuate surface 534 of a guide plate 536. After the capsule cover Cc has been introduced into the upper star wheel, another arcuate surface 538 of a guide plate 540 guides both capsule halves to their point of discharge from the combining mechanism 64.

As best illustrated in FIGS. 34, 35 and 38, the capsule covers Cc which are accumulated in the cover track 54 are powered into the combining mechanism first by a wheel 542 such as a sponge rubber wheel keyed to a shaft 544 that is driven in the direction of the arrow (FIG. 34) by any suitable drive means such as a motor 546. In addition to the wheel 542, an endless cover conveyor 548 (FIG. 34) is trained around a drive pulley 550, a driven pulley 552, and a plurality of idler pulleys 554 all suitably journaled on the frame F. The upper run of the cover conveyor 548 is driven in the direction of the arrow in FIG. 38. As illustrated in FIG. 35, the capsule cover Cc, when supported on the conveyor 548 are guided by edge guide rails 556 and top guide rails 558.

In order to accurately align the capsule covers Cc with the capsule bottoms Cb, the discharge end of the rails 556 and 558 are angled so that the capsule cover Cc move substantially radially into the pockets 524 of the upper star wheel 522. The end capsule cover Cc when entering an empty pocket 524 is advanced at sufficient speed by the conveyor 548 to move completely into the pocket over the capsule bottom Cb before dropping onto the capsule bottom. Thus, there is no sliding action between the capsule cover Cc and the capsule bottom Cb, which sliding action would smear the glue and tend to foul the combining mechanism 64.

The gluing mechanism or pump 60 (FIGS. 33, 34, 36 and 37) is mounted on a bracket 564 secured to the frame F of the machine. The gluing mechanism 60 comprises a glue dispensing chamber 566 (FIGS. 36 and 37) having openings 568 and 570 in its upper wall 572 and lower wall 574, respectively. A dispensing head 576 is secured to the lower chamber wall 574 and is ported to receive a plurality, preferably four, glue dispensing nozzles 578. Each nozzle 578 is generally frusto-conical in cross-section and is provided with a small diameter orifice 580 extending therethrough.

A glue receiving cup 582 having an open upper end is rigidly connected to an outer wall of the dispensing chamber 566, and the outer wall and cup 582 are provided with a port 583 to provide fluid flow communication between the cup 582 and the chamber 566. A supply of glue is contained in a bottle 584 (FIG. 33) having an open neck 586 which is supported within a ring 588 rigidly secured to the chamber 566. The ring 588 is positioned so as to support the inverted bottle 584 with its neck below the open upper end of the cup 582 and above the port 583 so that glue will flow from the bottle into the cup 582 and then through the port 583 into the chamber 566 to maintain a glue level in the cup and in the chamber equal to that illustrated in FIG. 37.

The glue dispensing chamber 566 is releasably clamped to a vertical wall of the bracket 564 by a clamp 590. The clamp 590 (FIG. 36) includes a sleeve 592 secured to the bracket with a bolt 594 journaled therein. A clamp arm 596 is keyed to the bolt 594 and is urged outwardly by spring 598. A clamp screw 600 is threaded in the free end of the arm 596 and may be tightened by hand to clamp the glue dispensing chamber 566 and the supply bottle 584 in the operative position illustrated in FIG. 36. When it is desired to remove the dispensing chamber from the machine, the clamp screw 600 is loosened and the arm 596 is pivoted upwardly away from the chamber 566 for removal as will be described hereinafter.

In order to dispense spots 62 of glue onto a capsule base *Cb* while the base is moving continuously, a solenoid 602 is mounted on the bracket 564 and is energized and de-energized once for each capsule base *Cb* moving therewith. The solenoid 602 includes an armature rod 604 that is urged downwardly by spring 606 disposed between the solenoid housing and a nut 608 screwed on the armature rod. A key 610 is secured to and projects outwardly from both sides of the lower end of the armature rod 604 for reception in notches 612 (FIGS. 34 and 36) formed in the wall of a tube 614 slidably received on the armature rod 604.

The tube 614 is rigidly secured to a crossbar 616 which is apertured and is guided for vertical reciprocal movement by the reduced diameter portion 618 (FIG. 37) of a pair of guide rods 620 (only one being shown in FIG. 37). The guide rods 620 are secured to the upper wall 572 and lower wall 574 of the glue dispensing chamber 566, and resilient washers 622 are mounted at both ends of the reduced diameter portion 618 of the guide rod 620 to reduce noise and cushion impact when the cross bar 616 reaches the ends of its stroke.

In order to dispense a predetermined amount of glue from each glue dispensing nozzle 578, a plurality of rods 624, one for each glue dispensing nozzle 578, are provided. The rods 624 are rigidly secured to the cross bar 616 and have reduced diameter end portion 626 which are aligned with the orifices 580 in the associated nozzles 578. When the solenoid 602 is energized, the end portion 626 of the rods raise above the nozzles as indicated in FIG. 37 allowing a slug of glue to fill each nozzle orifice 580. De-energization of the solenoid 602 then causes the spring 606 to lower the rod end portion 626 through the associated orifices thus positively discharging the slugs of glue onto the capsule base *Cb* as the capsule base *Cb* is continuously moved therewith by star wheel 504 as indicated in FIG. 36.

It is apparent that the slot 612 and key 610 (FIG. 36) which provides the sole connection between the sleeve 614 and the solenoid rod 604 allows the glue dispenser 566 and associated parts to be easily and rapidly removed from the machine for cleaning and replacement after the clamp 590 has first been loosened and pivoted away from the glue dispensing chamber 566.

The capsule combining mechanism 64 (FIGS. 33, 35 and 38) includes the previously described capsule advancing star wheels 520 and 522, and the other previously described parts mounted on or adjacent to the shaft 526. A pressure applying mechanism 630 is also carried by the shaft 526 and includes an upper disc 632 and a lower disc 634 rigidly secured to the shaft 526. Each disc has a plurality of equally spaced apertures

636 therein with the apertures in one disc being aligned with an aperture in the other disc and also in alignment with one of the capsule advancing star wheel pockets 518, 524.

5 Each aligned set of apertures 636 (FIG. 38) slidably receives a pressure applying piston 638 which is grooved near its upper end to receive a snap ring 640 to limit the upward movement of the piston 638. A compression spring 641 is disposed between the snap ring 640 and the lower disc 634 for applying an upward preloaded force of about 2 pounds to the piston. Each piston is provided with a bore 642 and a counterbore 644 defining a shoulder 646 for seating a compression spring 648. A pressure applying rod 650 having a large 15 diameter collar 652 for engaging the other end of the compression spring is slidably received in the bore 642 and in a sleeve 654. The sleeve 654 is locked to the piston and provides a flange which engages the collar 652 to limit upward movement of the rod 650 by the spring 20 648 which is prestressed at about 5 pounds.

After both halves of the capsule have been introduced into the combining station as previously described, the upper rounded ends of the pressure applying rods 650 are moved into engagement with a downwardly inclined camming surface 658 of a cam 660 causing the entire piston 638 to first move downwardly against the capsule halves to initially force them together with a light pressure. As the rods 650 move further downwardly to the lowermost horizontal portion 30 662 of the cam 660, the capsule halves resist further downward movement of piston 638 and accordingly only the rod 650 moves downwardly against the urging of the compression spring 648. A pressure of about three to four pounds is maintained on the capsule as the rod moves along the flat portion 662, and thereafter the rod contacts an upwardly inclined camming surface 35 664 of cam 660 and gradually releases its pressure on the capsule C. The rod 650 then moves away from the cam 660 allowing the pressure upon the piston 638 to 40 move to its uppermost position spaced from the completed capsule C (FIG. 35). The capsule is then stripped from the combining mechanism 64 by the stripper plate 530 and is discharged over deadplate 532 onto the take-away conveyor 500 for subsequently 45 packaging or the like.

Although during normal operation capsule bottoms *Cb* are accumulated and fed to the capsule combining and gluing mechanism 61 in abutting relationship by 50 accumulating conveyor 270 and feed conveyor 505, an underfeed or capsule bottom stopping mechanism 670 (FIGS. 33, 35, 39 and 40) is provided to stop the capsule bases or bottoms *Cb* in the event a void or underfeed occurs in the capsule bottom supply leading into the gluing mechanism 60. The capsule stopping mechanism is preferably located approximately three capsule lengths ahead of the glue discharge point of the gluing mechanism 61 as illustrated in FIGS. 33 and 35. The capsule bottoms are supported by the feed conveyor 55 505 and are guided by the edge rails 262 and the upper or hold down rails 264 as they enter the capsule bottom stopping mechanism 670.

60 The capsule bottom stopping mechanism 670 (FIGS. 39 and 40) comprises a photoelectric cell 672 mounted on a bracket 674 secured to the frame F, and a cooperating light source 676 mounted on a bracket 678 secured to one of the rails 264. The photoelectric cell 672 and light source 676 are angled relative to a verti-

cal plane as indicated in FIG. 40 so that the light beam 679 will pass between the belts 505a and 505b of feed conveyor 505 as indicated in FIG. 40. If the photoelectric cell 672 sees light, it is necessary to block the path of travel of subsequent capsule bottoms Cb to assure that the capsule bottoms will not be out of time with the pockets 510 of star wheel 504 and be crushed when attempting to enter the pockets.

Accordingly, when the photoelectric cell 672 sees light, the cell activates an underfeed solenoid 680 to lift a V-shaped abutment 682 (FIG. 39), formed on the end of a sleeve 684 threaded on the solenoid stem 686, upwardly into the path of movement of the capsule bottoms Cb to prevent further movement of capsule bottoms therewith. The solenoid 680 is secured to the bracket 678 and has a spring 688 secured between a pin 690 secured to the sleeve 686 and an L-shaped arm 691 secured to one of the rails 262 to normally hold the V-shaped abutment 682 below the path of travel of the capsule bottoms Cb.

A control circuit which is within the skill of the art and accordingly will not be described in detail, is provided to connect the photoelectric cell 672 to the underfeed solenoid 680 and to the glue pump solenoid 602 (FIG. 33) of the gluing mechanism 60. When the photoelectric cell 672 sees light, the control circuit energizes underfeed solenoid 680 to block further movement of capsule bottoms Cb into the gluing mechanism 60. However, the control circuit does not deactivate the glue pump solenoid 602 until the three capsule halves downstream of the base stopping mechanism 670 (FIG. 35) have moved past the gluing mechanism 60 and have received glue. The count is accomplished by a single reed or vane switch SW-4 (FIGS. 32 and 33) which is activated each time a finger 702 of a multi-fingered disc 704 keyed to the glue pump shaft 512 passes through the reed switch SW-4. The disc 704 has the same number of fingers 702 thereon as the star wheel 504 has fingers which define the pockets 510.

After the underfeed condition has been corrected and the light source 676 is again blocked by a capsule base Cb, the control circuit retains the glue pump solenoid 602 inactive for three counts after the underfeed solenoid 680 has been de-energized to prevent discharge of glue when no capsule bottoms Cb are present to receive the glue, and thereafter allows the solenoid to resume its normal dispensing action. The underfeed solenoid 680, however, is not de-energized until a single finger 706 of a disc 708 passes through a single reed or vane switch SW-5.

The drive mechanism 712 for the capsule combining and gluing mechanism 61 and for the capsule bottom accumulating conveyors 272 is best illustrated in FIGS. 41-43. The drive 712 is powered by a variable speed motor 714 which is connected to the input shaft of a right angle gear box 716 by a chain drive 718. The output of the gear box 716 is connected by a V-belt drive 720 to the shaft 228 which drives the conveyor 210 which feeds capsule bottoms Cb into the singulating mechanism 58, and also drives the conveyor 548 which feeds capsule covers Cc into the capsule combining and gluing mechanism 61.

A second output shaft from the gear box 716 is connected to a second right angle gear box 722 by a chain drive 724. The output of the gear box 722 is connected to the glue mechanism shaft 512 by a chain drive 726. The shaft 512 drives the shaft 526 of the combining

mechanism 64 by a gear drive 728 with the direction of rotation being indicated by arrows.

A chain drive 730 connects the shaft 512 to the input of a third gear box 732. The output shaft 734 of the gear box 732 has two equal size sprockets 736 and 738 thereon. As indicated in FIGS. 42 and 43, the sprocket 736 is connected to a small diameter sprocket 740 by a chain 742. The sprocket 740 is keyed to a shaft 744 to which the drive pulley 506 of the capsule feed conveyor 505 and the belt 266 of the capsule bottom accumulator 270 are keyed. The sprocket 738 is connected to a large sprocket 746 by a chain 748. The sprocket 746 is rigidly secured to the drive pulley 508 of belt 268, and the drive pulley 508 is journaled on the shaft 744. Thus, the belts 266 and 268 of accumulator conveyor 270 are driven at different speeds causing the capsule bottoms Cb to rotate as indicated in FIG. 43 and, if broken, to rotate to a position where it will fall between the belts 266 and 268 as indicated in FIG. 44.

From the foregoing description it will be apparent that the capsule assembly machine rapidly and gently separates and orients capsule halves into capsule bottoms and capsule covers each having a cavity therein. A seed singulating mechanism then drops a single seed into the cavity in each capsule bottom, and if a seed is not dropped, or if an over-supply of capsule bottoms accumulate, then a photoelectric control mechanism discharges that capsule bottom from the capsule bottom processing row. The loaded capsule bottoms then enter the capsule combining and gluing mechanism at which time glue is applied to each capsule bottom and a capsule cover is then aligned and pressed into sealing engagement with the associated bottom to encapsulate a seed into the capsule halves to provide a complete capsule with a single seed therein.

Although the preferred embodiment of the capsule assembly machine is designed to encapsulate single seeds, it will be understood that other similar articles may be singulated and encapsulated by the machine. Accordingly, the term "seed" as used in the specification and claims is to be construed broadly enough to include equivalent articles to be encapsulated.

Although the best mode contemplated for carrying out the present invention has been herein shown and described, it will be apparent that modification and variation may be made without departing from what is regarded to be the subject matter of the invention.

What we claim is:

1. Apparatus for applying adhesive to capsule discs comprising a conveyor for a row of the discs, a rotating star wheel having pockets for receiving the discs from said row, an adhesive dispenser above one of said star wheel pockets and timed to deposit adhesive on each underlying disc, a movable stop positioned at said conveyor for leaving a predetermined number of the discs between the stop and said adhesive dispenser, a capsule disc detector just upstream of said stop, and control means connected between said detector and said adhesive dispenser, said control means including count-producing means activated when said disc detector determines that an empty space rather than a disc is positioned just upstream of said stop, the activated count-producing means then counting off said predetermined number of discs between said stop and said dispenser position, said control means interposing said stop when no capsule disc is present just upstream of said stop, said control means thereafter interrupting dispenser

operation after said predetermined number of capsule discs between said stop and said dispenser have been advanced under the dispenser.

2. The apparatus of claim 1 wherein said control means withdraws said stop upon sensing of a capsule disc by said detector and thereafter restores operation of said dispenser after said predetermined number of capsule halves passes by said detector in a continuous row.

3. The apparatus of claim 1, comprising electro magnetic means for operating said adhesive dispenser, dispenser operation signal means movable in synchronism with said star wheel, and control means connecting said signal means to the electromagnetic operating means for said dispenser.

4. Apparatus for depositing a droplet of an adhesive on a seed capsule half or the like, said apparatus comprising an adhesive chamber having a liquid dispensing passageway in its bottom wall, a dispensing pin in said chamber that fits snugly within said passageway, means

10 20 15

for supplying adhesive to said chamber, pin operating means for lowering said pin into and through to the bottom of said passageway to eject the droplet of adhesive which is contained in said passageway and for subsequently raising said pin so as to clear said passageway, means for feeding capsule halves or the like beneath said chamber, and control means for lowering said dispensing pin when a capsule half is beneath said chamber.

5. The apparatus of claim 4, wherein said pin operating means comprises a spring for lowering the pin and a solenoid for raising it, means for sensing the positioning of a capsule half under said adhesive chamber, means for deenergizing said solenoid to permit said spring to lower said dispensing pin when a capsule half is so positioned, and means for energizing the solenoid to raise the dispensing pin before the next capsule half reaches said adhesive chamber.
